UNITED STATES PATENT OFFICE.

THÉODORE HAUSCHEL, OF REIMS, FRANCE.

APPARATUS FOR DYEING, &c.

SPECIFICATION forming part of Letters Patent No. 362,620, dated May 10, 1887.

Application filed January 5, 1887. Serial No. 223,430. (No model.) Patented in France August 22, 1884, No. 163,899; in Belgium August 22, 1884, No. 66,093; in Italy September 30, 1884, No. 17,300; in Austria-Hungary July 3, 1885, No. 19,755 and No. 33,632, and in England June 22, 1886, No. 8,249.

To all whom it may concern:

Be it known that I, THÉODORE HAUSCHEL, a citizen of the French Republic, residing at Reims, in said Republic, have invented new and useful Improvements in Apparatus for Dyeing, Carbonizing, and Drying Textile Materials, of which the following is a specification, reference being had to the accompanying drawings.

10 The object of this invention is to provide an apparatus for the washing, the carbonization, the maceration, and the dyeing of wool, cotton, and other textile materials by which an easy and rapid manipulation is provided for and the loss of coloring-matters after each 15 operation, when the following operation requires a different color, is obviated.

The apparatus which embodies my improvements effects the dyeing by a continuous passage 20 of the dye-stuffs through the fabrics by means of a system of pumps, vats, and canalization, forming a battery. By the simple operation of cocks or gates the different dye-stuffs are caused to pass through the fabrics, 25 the dye-stuffs being supplied from different vats, which recover them after their employment. By this means I effect in a very simple and rapid manner, and without loss of colors, all that is effected by the more or less complicated and costly manipulations in use up to 30 the present time in this kind of industry.

The detailed description which follows will enable, by the aid of the accompanying drawings, the construction and operation of my invention to be understood.

Figure 1 represents a vertical section of a complete apparatus. Fig. 2 represents a central longitudinal section of one of the perforated tubes which form canals. Fig. 2^a represents 40 a transverse section of the said tube; Fig. 2^b, a longitudinal view of the plunger with which said tube is fitted. Fig. 3 is a plan of a device for working the said plunger. Fig. 3^a is a central section corresponding with Fig. 3. 45 Fig. 4 represents a modification of a part of the apparatus employed in case of the dyeing of raw or uncarded products, and Fig. 5 is a plan view corresponding with Fig. 4.

Similar letters of reference designate corresponding parts in all the figures. 50

My apparatus is composed of the following organs:

First. A series of vats, A A', with valve at their bottom serving for the preparation of different tinctorial products and arranged 55 symmetrically with relation to the general axis of the battery, the center of which is the pump B.

Second. Two other vats, C C', like the first named, but of a larger capacity, placed on 60 each side of the pump and communicating with it by means of tubes D, furnished with cocks E' and E².

Third. A tank, F, placed at a lower level than the vats hereinabove mentioned and furnished with a draining-well, into which dips a tube, D, furnished with a cock, E, which puts it in communication with the pump. 65

Fourth. Two other tanks, G G', placed above the vats C C', and through the bottoms of which 70 pass branches of the tube D, these tanks G G' being furnished each with two orifices with cocks or gates, of which one communicates by the tubes K K', furnished with cocks K* K*, with the vats C C', and the other by the canals 75 L L' and the tubes M M', furnished each with cocks, with the several vats A A'. Each of the tanks G G' contains a tube, V or V', passing through its bottom, said tubes being open ends being arranged at the highest level that the liquors should reach in the tanks G G'. 80

Fifth. The two series of perforated tubes H, of which there may be any number, furnished internally with a system of special stoppers, I, and forming beams upon which are directly wound the textile matters to be dyed, these perforated tubes, represented on a larger scale in Fig. 2, being divided longitudinally or constructed of two semi-cylindrical parts 90 bound together by rings or bands J, and the perforations being conical in order to provide for the easy cleaning of the apparatus, a system of bayonet-joints, X, permitting their being rapidly attached to branches of the tube D. 95

Sixth. These stoppers I have for their pur-

pose the limiting of the level to which the dye-stuffs may enter into the tubes H, according to the height to which the fabrics are wound upon the said tubes. The said stoppers have each 5 formed on its lower part a metallic cone, c, fitted with a cup-packing of felt, d, which is held in place by the same in a fixed position between a collar, f, and a nut, e. The upper part of the stem of the stopper is furnished 10 for a certain length with a screw-thread, which is fitted to a nut, b, which is fitted to turn freely, but confined lengthwise within a yoke, A, articulated to a plate, S', which serves to compress the fabric to each perforated tube or 15 beam H. These screw-threads and nuts serve to regulate at will the height of the stoppers.

Seventh. Two canals, N N', to permit the descent of the contents of the vats A A', placed above them, into the tank F.

20 Eighth. The pump B, which communicates by the conduits E and cocks E' E' E' E' with the tanks F C C' and the tubes H, causing the liquors in these tanks to circulate through the tubes H, and consequently through the fabrics 25 which are wound thereon.

Ninth. A water-conduit, O, running the whole length of the apparatus, is intended to feed the different vats hereinabove described.

Tenth. A steam-pipe for heating the different vats A A C C'.

Eleventh. A connection with the conduits D, permitting the sending, for the purpose of carbonization, of a current of hot air through the perforated tubes, and consequently through 35 the textile materials.

Twelfth. Two tubes, W W', furnished with cocks W* W** and abutting, respectively, at one end between the cocks E' U' E' U and at the other end near the cocks E' E'.

140 Thirteenth. A curved tube, X, provided with a cock, X', and with a joint, Y, which permits it to turn in such manner that it may debouch either in the vat G or G'.

The operation of this apparatus is performed 45 as follows: The perforated tubes H are first placed in a loom or in a winding-machine, and have therein rolled upon them the materials to be dyed in such a manner as to form one or more distinct bobbins separated by washers 50 of felt placed between them, and against the latter is placed the plate S', represented in Fig. 3, to tighten them up together, either by means of wedges or in any other manner, against each other. This having been done, if the 55 quantity of material to be treated is not sufficient to cover the whole height of the tube, the position of the stoppers I is so adjusted that the liquid which will penetrate into the tubes H cannot rise above the level of the material wound thereon. Then these tubes are

60 attached to the branches of the tube D, which debouch into the tanks G G' by means of a bayonet-joint. The exterior of the surface of the material wound on the tube H is free and 65 not inclosed, as in other apparatus for the same purpose, in perforated metallic envelopes, which have the bad effect at the mo-

ment of the passage of the coloring-matters to deteriorate the fibres treated.

During the winding of the material about 70 the tubes H the different dyes which are to be used may be prepared in the vats A A', and when one of them is needed, the valve of that one of the said vats corresponding with this dye is opened. The contents of the said vat then descend into the tank F, and the pump causes them to circulate through the material, either by traversing the interior of the tubes H towards the exterior of the wound matters or, on the contrary, from the exterior 75 of the wound matters toward the interior of the tubes H, and in both cases by turning the pump in one direction or the other by the simple employment of cocks. This arrangement permits the dyeing of the same materials 80 successively by the two processes, in order to have a perfectly uniform dye throughout the 85 whole thickness of the mass.

Only one of the two series of tubes H, with the material to be dyed wound upon it, is in 90 process of dyeing, while the other is having the material wound upon it, and thereby a continuous operation is provided for. Suppose that the series of tubes H placed at the right of the pump is in process of dyeing, while 95 the other series is in preparation. I then open the cocks E E' E' and the valve of the tube K, and I close E' E' and the valve of the canal L', as well as the cocks W*, W**, X', and K**. The pump B will then draw the dye from the 100 drain-well of the tank F and force it through the tubes H, causing it to filter through the material wound upon the said tubes, whence it will descend, first, through the tank G', filling it up to the upper level of the tube V', 105 and escaping by the latter into the vat C'. At this moment the cock E is closed, and the valve at the bottom of C being closed the die 110 will then be drawn by the pump by passing through the cock E', and the dye will continue 115 to circulate in a continuous manner until it is judged convenient to arrest the circulation—i. e., until the materials have the tint required.

During the treatment above described the 120 series of tubes H on the left have been re-wound with materials to be dyed and are replaced in the tank G. Then I close the cock E', I open E' and E', I close K', and cause the 125 passage of the dye contained in the vat C' through the tubes H on the left. Once this vat is emptied I close E', and the circulation of the dye is effected through the conduit system D of the tubes H of the vat C on the left, in the same manner as has been described with reference to the vessels on the right. To completely empty the tanks G G' it is only necessary to open the cocks K' and K**.

When after one operation more dye is wanted, what had been previously prepared having been absorbed by the passage through the tubes 130 H and material wound thereon, new dye may be prepared directly in the vats C C', if it is desired to continue the use of the same color. These vats, termed "extractors," serve also

for the direct preparation of the dyes every time it is desired to obtain them from dye-woods. In such case I place in the middle of the vats C C' one or more little perforated vats 5 filled with dye-stuff. These vats are supported in such manner as not to touch the walls of the vats C C'. The current of dye, which circulates as I have hereinabove described, passes continually around and through these small 10 vats containing the dye-woods and takes up, as fast as its successive passages are made, a more or less deep color, which is in excellent condition to obtain a good dyeing of the materials under treatment.

15 When it is desired to change the dye, the dye-liquor, which is no more required to be used, is collected in the vat intended for that color, by closing the cock of the tube K or K', and opening that of the canal L or L' and 20 that of the tube M or M', corresponding with the said vat. I then cause the new dye to be employed to be delivered from one of the vats A A' into the tank F, as has been hereinabove described, and the operations are repeated in 25 the same manner.

In those cases in which, instead of having to dye woven or carded materials, it is desired to treat raw fibers or products, instead of fixing the tubes H of each branch on the tubes D, 30 I employ the apparatus represented in Figs. 4 and 5. This apparatus is composed of a circular box, Q, upon which rests a movable plate, E, through which pass tubes H, with internal stoppers like those before described, 35 and of which there may be any convenient number and held in place by a bayonet-engagement with openings in the top of the circular box Q. To pack the raw material between these tubes H, I place upon the plate P 40 a movable hollow cylinder, V, having its sides perforated with numerous holes. I then stuff into this cylinder, around and between the tubes H, the materials to be dyed, and afterward place above them the cover S, and subject the whole to the action of a press. Then, 45 by means of bars passing through the holes in the cylinder, I retain the compression of the matter while I withdraw the cover S and pack in a new quantity of material, repeating the 50 operation as often as is necessary, until the tubes H are surrounded throughout their whole height with the products to be operated upon. I then withdraw the metallic cylinder V, the cover S being maintained attached by 55 means of hooks to the plate P. I have on this plate a cylinder of compressed matter through which pass a number of perforated tubes, H.

The operation of dyeing is then performed as I have above described in the case of woven 60 or carded matters, arranged by winding upon the tubes H, as shown in Fig. 1.

It may be understood from the foregoing description how, either in the case of woven or carded fabrics wound upon the tubes H, and in the case of raw materials, I effect the dyeing 65 by a current of liquid dye traversing the fabrics or material from the inside to the outside. When it is desired, on the contrary, to dye by a current passing through the material from the outside to the inside, I operate 70 in the following manner: Suppose I operate with the tubes H on the right-hand side of the pump. The cocks E', W*, and E³ are closed to shut off the tubes H on the left. The cock E' E², according as it is desired to use the 75 color in the tank F or vat C', is opened. The cock X' is opened. The cocks E, U', and W* are closed at the beginning of the operation. When the pump has supplied, by the tube X, sufficient dye-liquor into the tank C' to nearly 80 fill it, I close the cock E' E², which was at first open. Then I open the cocks U' W* and the dye-liquors circulate then in a closed cycle, which is as follows: The vat G', the tube D, the cock U', and the tube W W', and are then 85 drawn from the vat by the pump through the vertical tube D, and the liquors so drawn are forced through the tube X to be returned to the tank G'. It will be readily understood that this operation may be performed through the other 90 vat, G, in the same manner, by opening and closing the proper cocks.

What I claim as my invention, and desire to secure by Letters Patent, is—

1. The combination, with the tank G or G' 95 and the perforated tubes H therein, of adjustable stoppers in said tubes for shutting off a portion of their length, as and for the purpose herein set forth.

2. The combination, with a tank, as G or G', 100 and its contained perforated tubes H, of the pump B and its pipes D, W, W', and X Y, for the purpose of delivering liquor to the said tank outside of the said tubes and taking it therefrom through the perforations of said 105 tubes, substantially as herein described.

3. The combination, with a plurality of tanks, G G', furnished with perforated tubes H, a pump, and connections with the bottoms of the said tubes for drawing liquor through 110 them from either of said tanks and cocks for closing said connections with either tank, of a swinging delivery-pipe, X Y, for producing the delivery of the liquor to either tank, substantially as herein described. 115

In testimony whereof I have signed this specification in the presence of two subscribing witnesses.

THÉODORE HAUSCHEL.
